Waukegan, Ill., assignors to Johnson Brothers
Engineering Corporation, South Bend, Ind., a
corporation of Indiana

Application December 14, 1932, Serial No. 647,080

4 Claims. (Cl. 115—17)

This invention relates in general to an outboard motor and has more particular reference to a combined steering and carrying handle therefor.

5 One of the principal objects of the invention is in the provision of an adjustable handle which may be connected for turning the motor in steering and adjusted into a different position for carrying the motor by hand.

10 A further object of the invention is in the provision of means for engaging a handle for balancing a motor both longitudinally and transversely for carrying it more easily.

Other objects of the invention will appear 15 hereinafter, the preferred construction being illustrated in the accompanying drawing.

In the drawing, Fig. 1 is a side elevation of an outboard motor to which this invention is applied, in carrying position;

20 Fig. 2 is a top view of the motor showing the positions of the steering and carrying handle; and

Fig. 3 is an elevation of the steering handle and the steering rail in their motor carrying relation.

25 The ordinary outboard motor is sufficiently heavy to be somewhat of a problem for one person to carry as the motor is located at the upper end of a drive shaft and the propeller is located at the opposite end of the shaft and no suitable means is provided for grasping the motor and transporting it from one place to the other. The present invention provides a handle which also functions as a tiller in turning the motor for 30 steering, the handle being adjustable to either one of two positions, in one of which it is set against rotation and at an angle to the other position so that it is parallel with the length of the motor and located substantially at the 35 longitudinal and transverse centers thereof so that the entire motor is thus balanced and easily carried.

40 Referring now more particularly to the drawing, a conventional form of outboard motor is shown having an engine 4, muffler 5, gas tank 6 and other accessories at one end, a longitudinally extending casing 7, a lower casing 8, and a propeller wheel 9 at the other end.

45 Extending laterally from the engine end of the motor is a rail 10 which protects a carburetor 11 and some of the other parts and is commonly used for supporting and upholding the motor and also for steering. This rail is preferably angular in structure with arms 12 extending from 50 the outer rail 10 to the motor.

The entire motor is mounted in a bracket 13 which is adapted to be attached to the stern of a boat, the motor being mounted to tilt upwardly upon a pivot 14 and rotatable for steering in a sleeve portion 15 to which the bracket 13 is pivoted.

55 In order to steer a boat to which the motor is applied, the motor is turned in the sleeve portion 15 or about a longitudinal axis and for this purpose the rail 10 or its arms 12 may be grasped and the motor rotated. For convenience a handle 16 is provided having an arm 17 connecting it with an angular member 18 which has a portion underlying the rail 10 with an angular extension 19 to underlie the angular arm 15 12 and partially embrace it, the member being 20 held in pivotal relation upon the bar 10 by a cap 21 which is pivoted to the under member 18 at one side by means of a pivot 21 and releasably attached at the other side by means of a thumb screw 22.

25 In steering a boat this construction permits the motor to tilt rearwardly upward, if an obstruction is encountered in the water, without violently jerking the handle which is normally in the broken line position shown in Fig. 2. It will also be seen that the handle 16 is disposed at an angle by the member 18 so that even if the motor is thrown upwardly, the person or the hand guiding the handle will not be struck.

30 At the other side of the bar 10 remote from the angular steering corner is a projection 24 and in the edge of the cap member 20 is a notch 25 to engage the projection 24, the projection being located so that the handle 16 and 35 the attaching members 18 and 20 must be rotated about at right angles to the steering position to engage therewith. This places the handle 16 substantially parallel with the longitudinal extent of the motor and at the center both longitudinally and transversely of the motor mass, so that when grasped in this position by a single hand, the motor is substantially balanced in both directions and can be easily grasped and carried.

40 Thus the same handle which is used for steering is adjusted in position and utilized for balancing and carrying the motor. To disengage the handle 16 from steering position it is necessary to raise it about its pivot until the extension 19 is clear of the arm 12. The cap member 20 45 may be loosened and tightened to move the handle more easily and to hold it in either adjusted position.

45 It will be apparent that the construction of the motor does not affect this invention. It may 50

be necessary to alter the location of the projection 24 or the length or angle of the handle dependent upon the size or variation of the motor parts; and the invention is equally applicable to 5 an outboard motor of the type in which the lower drive portion but not the motor is turnable for steering.

We claim:

1. In an outboard motor, a steering rail, a tiller pivoted thereto, a projection on the rail, and means for adjusting the tiller angularly and along the rail in engagement with the projection to change its normal angle thereto and for carrying the motor.
- 10 2. The combination with an angular steering rail of an outboard motor, of a tiller pivoted upon one arm and engageable in normal position with the other, and a projection on the pivoting arm engaged by the tiller in a different angular position
- 15

for holding them fixedly together for carrying a motor.

3. An outboard motor having a steering rail with an angular portion and a projection at a distance therefrom, and a tiller rotatable on the rail at the angular portion for steering and movable along the rail and into fixed engagement with the projection for carrying the motor.

4. The combination with an outboard motor having an angular rail, of a tiller pivoted thereon adjacent the corner thereof for steering, and interengaging means on the rail and on the tiller, said means on said rail being at a position distant from the rail corner, to dispose the tiller at a different angle for balancing and carrying the 10 motor with one hand.
